UNITED STATES PATENT OFFICE.

HERMANN WIESE, OF WALLACEBURG, ONTARIO, CANADA.

PROCESS OF REFINING SUGAR.

1,021,173.

Specification of Letters Patent. Patented Mar. 26, 1912.

Application filed January 9, 1912. Serial No. 670,169.

To all whom it may concern:

Be it known that I, HERMANN WIESE, a subject of the Emperor of Germany, residing at Wallaceburg, in the Province of Ontario and Dominion of Canada, have invented certain new and useful Improvements in Processes of Refining Sugar, of which the following is a specification, reference being had therein to the accompanying drawings.

10 The invention relates to process for the refining of sugar and has for its primary object a reduction in the time required for extracting sugar from the syrup.

15 It is a further object to obtain a higher degree of extraction, that is, to obtain a greater quantity of the sugar with a residuum molasses of lower grade or having a smaller percentage of sugar therein.

20 Still another object of the invention is to simplify and reduce the cost of apparatus required for the extraction process and to greatly economize in space required for such apparatus.

25 With these objects in view the invention consists in the process as hereinafter set forth.

In the drawings,—Figure 1 shows diagrammatically the apparatus which may be 30 used in carrying out my improved process. Fig. 2 is a plan of a modified device for mechanically agitating the mass.

35 In the present state of the art it is usual to concentrate the sugar juices for the initial crystallization of the sugar in vacuum pans. This concentration is however, only continued to obtain from 90 to 94% of dry substance and the further crystallization is carried on outside of the pans. It usually re-

40 quires from 24 to 72 hours' treatment in the vacuum pan with a stirring and cooling period of from 3 to 6 days in the crystallizers or mixers. Furthermore, the mother syrup or molasses is only reduced to about 65%

45 purity and the fillmasses are exposed to high temperatures for a considerable period of time, resulting in the destruction of a portion of the sugar and the formation of caramel. The long time required by the

50 process and particularly while in the crystallizers, necessitates apparatus of large capacity, which not only means high cost of installation but also requires a great deal of valuable space.

55 With my improved process the time required for the concentration of the juice to

a degree of from 95 to 96% of dry substance, and the complete extraction of the crystallizable sugar is only from 18 to 30 hours. Furthermore, the whole process is 60 carried out in the vacuum pan which dispenses with the crystallizers, thereby diminishing the cost of the apparatus and greatly 65 economizing in space. Still another advantage of my improved process is that the residuum molasses is of lower grade, which means that sugar which is present in the high grade molasses has been extracted.

In detail, the sugar juices or syrups are 70 first introduced into the vacuum pan such as A and are boiled down preferably under high vacuum until graining is effected, the temperature being preferably from 72 to 80% C. according to the purity of the juices or syrup, the higher the purity of the juices 75 the lower the temperature. As soon as a sufficient quantity of sugar grain of a proper size is obtained the boiling temperature is reduced slowly a few degrees and care is taken to avoid the boiling together 80 of the mass. An additional quantity of syrup or juice is then introduced in the pan which is regulated to avoid too great a thinning of the fluid, the density required varying according to the purity of juice or 85 syrup. It is desirable to avoid too sudden a change in temperature which in this stage of the process should be maintained from 68° to 72° C. After graining, fresh syrup or juice is again introduced and the same 90 process is repeated until the limit of capacity of the pan is reached, the successive drafts of syrup or juice are preferably equal in quantity and as before stated, the temperature is regulated to avoid sudden 95 changes. After the concentration of the last draft of syrup or juice in the pan the so-called "boiling together" is begun, maintaining the same temperature, and when the fillmass acquires a density at which in the 100 previous treatment, fresh juice or syrup is introduced, the vacuum in the pan is slightly raised with the resulting reduction in temperature. The circulation is increased by the increase of vacuum, giving 105 the mother syrup an opportunity to give up all its crystallizable sugar and to enlarge the crystals already made. This treatment is continued as long as the natural circulation of the mass may be maintained, any 110 reduction of which is indicated by a rise in the temperature. If the natural circula-

tion of the mass should cease, mechanical agitation of the mass is then begun, preferably by stirrers B which are arranged in the vacuum pan and which when in action 5 continue the circulation and agitation of the mass. Thus a concentration from 94 to 96.5% of dry substance is obtained. At the completion of the boiling the temperature will be about 65° C. and after the steam in 10 the heating coils C is shut-off the mechanical agitation is continued and the same vacuum is maintained. The temperature is permitted to drop and the cooling is preferably assisted by the circulation of cold 15 water from a tank D through the coil C and in this way practically all of the crystallizable sugar is extracted from the mother syrup. Thus the purity of residuum molasses is 60% or under, whereas in processes 20 heretofore used it was of higher grade.

In place of the stirring device illustrated in Fig. 1, I may substitute the means shown in Fig. 2 in which E is a perforated conduit arranged in the lower part of the vacuum 25 pan and connected with a source of air not shown. With this, whenever it is necessary to mechanically agitate the mass, air is introduced through this conduit which will force its way through the mass and produce 30 the necessary agitation.

What I claim as my invention is:

1. The process of extracting sugar from juice or syrup which consists in graining successive drafts of the juice or syrup in 35 a vacuum pan to a density of under 94% of dry substance, and in then continuing the concentration while the mass is still in the vacuum pan by forced circulation to a density from 94 to 96%.
- 40 2. The process of extracting sugar from juice or syrup which consists in concentrat-

ing and graining successive drafts of syrup in a vacuum pan to a density of under 94% in dry substance, and in then further concentrating the entire mass under higher 45 vacuum and forced circulation to a density of from 94 to 96.5%.

3. The process of extracting sugar from juice or syrup which consists in concentrating and graining successive drafts of the 50 syrup or juice in a vacuum pan at a temperature between 72 and 80° C., varying according to purity of the syrup and highest at the lowest purity, in then continuing the concentration under reduced temperature 55 and increased vacuum until the limit of natural circulation of the mass is attained, in then mechanically agitating the mass while still in the vacuum pan and further reducing the temperature until a concentration of from 94 to 96.5% dry substance is 60 obtained.

4. The process of extracting sugar from juice or syrup which consists in concentrating and graining successive drafts of the 65 juice or syrup in a vacuum pan to a degree of under 94% dry substance, in then continuing the concentration of the whole mass under increased vacuum and lower temperature until the limit of natural circulation is 70 reached, in then further continuing the concentration under forced circulation, and in then cooling and continuing the forced circulation or agitation, all of said operations being performed in the vacuum pan. 75

In testimony whereof I affix my signature in presence of two witnesses.

HERMANN WIESE.
